W. GRAH.
LOW LIQUID LEVEL ALARM.
APPLICATION FILED OCT. 14, 1920.

Patented Mar. 15, 1921.

FIG. 1.

FIG. 2.

INVENTOR

William Grah,
By Burnham & Crampton,
His Atty.

UNITED STATES PATENT OFFICE.

WILLIAM GRAH, OF WATERVILLE, OHIO.

LOW-LIQUID-LEVEL ALARM.

1,371,366.

Specification of Letters Patent. Patented Mar. 15, 1921.

Application filed October 14, 1920. Serial No. 416,852.

To all whom it may concern:

Be it known that I, WILLIAM GRAH, a citizen of the United States, and a resident of Waterville, county of Lucas, and State of Ohio, have made an Invention Appertaining to Low-Liquid-Level Alarms; and I do hereby declare the following to be a full, clear, and exact description of the invention, such as will enable others skilled in the art to which it appertains to make and use the same, reference being had to the accompanying drawings, and to the characters of reference marked thereon, which form a part of this specification.

This invention relates to audible alarms for use particularly in connection with the liquid containing tanks of automobiles to indicate a predetermined low liquid level condition therein, and the object of the invention is the provision of a simple and improved device for this purpose.

The invention is fully described in the following specification, and while in its broader aspect it is capable of embodiment in numerous forms, a preferred embodiment thereof is illustrated in the accompanying drawings, in which,

Figure 1 is a central vertical section of a liquid containing tank equipped with a device embodying the invention, and Fig. 2 is a fragmentary plan view thereof.

Referring to the drawings, 1 designates a liquid tank or container, for instance, the gasoline tank of an automobile, which tank has an opening 2, preferably in its top, through which the tank may be filled, the opening being closed by a removable cap 3.

In the present embodiment of the invention the cap 3 is provided on its top with an inverted U-shaped member or yoke 4, centrally within which is loosely suspended a bell, gong or other resonant member 5 for free vibratory or swinging movements relative to the cap. The member 5 is swingingly suspended from the yoke 4 in the present instance, by a rivet 6. A plurality of studs 7 are mounted on the top of the plug or closure member 3 in position to have striking contact with the edge of the resonant member 5 when rocked or vibrated, whereby said member is rung or sounded to transmit an alarm. The studs 7 are preferably normally spaced from the edge of the member 5 to permit a free rocking of the member relative thereto.

A float 8 is disposed within the tank 1

for riding on the liquid 9 therein, and a stem or rod 10 projects upward from the float loosely through a circular opening in the cap member 3 and into the interior of the bell or other resonant member 5. The upper end of the stem 10 is provided, in the present instance, with a head or enlargement 11 of disk form which, when the float is raised a predetermined extent, co-acts with and either lifts the resonant member 5 free from contact with the stationary striker studs or holds it against vibratory movements. The length of the stem 10 is such with respect to the depth of the tank 1 that when the liquid has reached a predetermined low level in the tank, the float 8 and connected parts will be lowered sufficiently to disengage the resonant member 5 and permit it to be freely rocked or oscillated into or out of striking contact with the studs 7 by the motion or vibratory action of the associated vehicle when running.

It is preferable to dispose the bell carrying member or yoke 4 without the bell so it may serve both as a protection for the bell and has a handle to facilitate a turning of the cap member 3 into or out of its opening. The yoke 4 in the present instance, is shown as having its feet secured to the cap 3 by screws 12.

I wish it understood that my invention is not limited to any specific construction, arrangement or form of the parts, as it is capable of numerous modifications and changes without departing from the spirit of the claims.

Having thus described my invention, what I claim as new and desire to secure by Letters Patent, is,

95

1. The combination with a liquid containing tank mounted for vibratory movements, of a resonant member carried by the tank for free rocking movements relative thereto, means with which the resonant member 100 when rocked may coact to sound a signal, and means actuated by the rising and falling of liquid within the tank to hold the resonant member inoperative when the liquid is above a predetermined low level position in the tank.

2. The combination with a liquid containing tank mounted for vibratory movements and having an opening in its top portion, a cap for closing said opening, a resonant member carried by the cap for free vibratory movements relative thereto, means car-

ried by the cap for coaction with the resonant member to sound a signal when the resonant member is free to rock, a float disposed in the tank, and means projecting upward from the float through the cap and adapted to permit a rocking of the resonant member to sound a signal when the float is at a predetermined low level position in the tank and to coact with the resonant member 10 to prevent a rocking thereof relative to the cap when the float is raised from its predetermined low level position.

3. In a vehicle, a liquid containing tank having an opening in its top portion, a removable cap for closing said opening and having a yoke member and a stationary stud rising therefrom, a resonant member sus-

pended from the yoke for free swinging movements relative thereto to permit it to strike the stud to sound a signal within the tank when vibrated by movements of the vehicle, a float in the tank, and means rising from the float to a point within the resonant member and adapted to permit movement of the gong to sound a signal 25 when liquid in the tank is below a predetermined level and to coact with the resonant member to prevent a signal sounding movement thereof when the liquid is above said level.

In testimony whereof I have hereunto signed my name to this specification.

WILLIAM GRAH.
